UNITED STATES PATENT OFFICE

SEDGWICK N. WIGHT, OF ROCHESTER, NEW YORK, ASSIGNOR TO GENERAL RAILWAY SIGNAL COMPANY, OF ROCHESTER, NEW YORK

TRAIN-DISPATCHING SYSTEM FOR RAILROADS

Application filed July 14, 1928. Serial No. 292,833.

This invention relates to train dispatching systems for single track railroads signaled with absolute-permissive-block signaling.

In my prior application Ser. No. 120,423 filed July 3, 1926 I have disclosed a train dispatching system in which the signals associated with opposite ends of a single track section, and the passing sidings adjacent thereto, are controlled by two relays one at each end of such single track section, and in which the direction traffic may travel over such single track section is determined by the sequence in which the levers are operated and the sequence in which the two control relays are energized. In my said prior application if a certain direction of travel has been set up in a single track section by a particular sequence of lever movement, this direction set up of travel can be disturbed and the reverse direction of travel accidentally set up, as for instance by a train entering such single track section at an intermediate point, possibly coming off of a spur track, or by workmen momentarily dropping a track relay, as by getting a steel crow bar across the track rails. This accidental reversal in the direction of traffic set up coming about by reason of momentary blocking of train travel in both directions, and if conditions are restored one of the two tumble-down circuits governing opposite direction of train travel is restored and the first one to be restored will prevail and set up its direction of travel and prevent the other tumble-down circuit being restored. In other words, in my prior application the direction of travel set up by sequence of lever movement was determined by the control relay which first caused a tumble-down circuit to drop all of the home relays associated therewith.

In accordance with the present invention, taking into consideration the foregoing, it is proposed to determine the direction of train travel by the sequence of lever movement and to provide means for preventing traffic to be set up in an opposite direction to that determined by such sequence. The net result to be accomplished, in accordance with the present invention is that if the direction of traffic set up is disturbed for any of the reasons

above mentioned, such direction of travel set up will be restored after such disturbance has terminated.

More specifically, it is proposed to employ a special or directional stick relay at each end of each single track section, and to permit one of these stick relays to pick up only in the event the other stick relay is still de-energized, as determined through the associated tumble-down circuit. In this connection it should be remembered that a short time is required for a tumble-down circuit to respond to the picking up of the stick relay. Another feature of the invention resides in the provision of indicating means for indicating when traffic is blocked in both directions as a result of operating the two levers associated with a particular single track section too quickly in succession.

Other objects, purposes, and characteristic features of the invention will in part be described hereinafter and in part be obvious from the accompanying drawings.

In describing the invention in detail reference will be made to the accompanying drawings in which:

Fig. 1 shows conventionally an embodiment of the present invention applied only to one particular single track section of a single track railway from which the indicating means has been omitted; and

Fig. 2 shows the same system, together with indicating means at the tower for indicating track circuit occupancy and indicating when traffic is blocked in both directions as a result of both of two supplemental stick relays being in their energized condition.

Referring to Fig. 1 of the drawings, showing a single track section O of a railway system having absolute-permissive-block signaling, as more completely shown in my prior application above mentioned, and including the passing sidings PS¹ and PS². The starting signals for the passing siding PS¹ has been designated 2 and 2^d, and the entering signals for this passing siding PS¹ have been designated 1 and 1^d. The exponent "d" indicated dwarf or take-siding, as the case may be. The starting signals at the west end of passing siding PS² have been designated 1^w

7 and 7^a and the entering signals have been designated 8 and 8^a. The intermediate signal for west bound traffic has been designated 3, and the intermediate signal for east bound traffic has been designated 6. Although the signals may be of any suitable construction such as color light or position light signals, for convenience semaphore signals only have been illustrated without showing their well-known control mechanisms and circuits. These signals are controlled by home relays such as 1H, 2H, 3H, 6H, 7H, and 8H, each having a number corresponding with the number of the signal. These various home relays are three-position or polar neutral relays, and are capable of controlling the corresponding signals to anyone of three indicating conditions in a well-known manner, through circuits for convenience not illustrated. Each of the intermediate signals, of which there may be a large number, such as signals 3 and 6 is provided with the usual directional stick relay, such as relays 3S and 6S, respectively. The passing siding PS¹ includes a track switch S¹ and the passing siding PS² includes a switch S². The signals associated with these switches S¹ and S² are protected by detector track circuits including the detector relays DT², and DT⁷ respectively, controlled by the track batteries illustrated. The remaining track circuits of single track section O, divided by insulating joints 4, include track relay 1T, 3T, 6T, and 8T each of which is connected to a track circuit including a track battery as illustrated. The starting signals 2, 2^a, 7, and 7^a are provided with signal blade-operated contacts 10, 11, 12, and 13, respectively; these contacts assuming the position shown when the signal blades, by which they are operated, assume the danger or stop position.

Let us now consider the tumble-down circuit for blocking west bound traffic, namely, the tumble-down circuit controlling the home relays 3H and 7H. In this connection it should be noted that the home relay 3H is energized by the following circuit:—starting at the battery B, back contact 15 of the auxiliary stick relay ZS¹, contacts 10 and 11 controlled by the signals 2 and 2^a respectively, a front contact 16 of the detector track relay DT², contact 17 of the track relay 1T, and a contact 18 of the track relay 3T. Also it should be noted that de-energization of the home relay 3H will cause de-energization of the home relay 7H unless the stick relay 3S is up. The energizing circuit for the home relay 7H comprises of the following:—beginning at B of a suitable source of current, front contact 20 of the home relay 3H or contact 19 of the stick relay 3S back contact 21 of the stick relay 6S, front contact 22 of the track relay 6T, front contact 23 of the track relay 8T, front contact 24 of the detector track relay DT⁷ through the winding of relay

7H to the common return wire C connected to the other side of said source.

In the same way the home relay 6H is energized by the following circuit:—beginning at the terminal B, back contact 25 of the auxiliary stick relay ZS², signal blade operated contacts 13 and 12 of the signals 7^a and 7 respectively, contact 26 of the detector relay DT⁷, contact 27 of the track relay 8T, contact 28 of the track relay 6T through the winding of relay 6H to common return C. The circuit for the home relay 2H is controlled by home relay 6H and may be traced as follows:—beginning at the terminal B, front contact 30 of the relay 6H or front contact 29 of the stick relay 6S, back contact 31 of the stick relay 3S, front contact 32 of the track relay 3T, front contact 33 of the track relay 1T, front contact 34 of the detector track relay DT² through the winding of relay 2H to the common return wire C.

It is thus noted that energization of the auxiliary relay ZS¹ at the west end of the single track section O is manifested by dropping of the home relay 7H at the east end of this single track section; and conversely, energization of the auxiliary stick relay ZS² at the east end of the single track section O is manifested by de-energization of the home relay 2H in the west end of this single track section, these manifestations being carried through the medium of the two tumble-down circuits. In this connection it should be noted that the pick up circuits for these auxiliary stick relays ZS¹ and ZS², include front contacts of the adjacent home relays, and that back contact of each of these stick relays determines the energization of the home relay adjacent to the other auxiliary stick relay, so that these stick relays are in fact interlocked through the tumble-down circuits.

The system under consideration is controlled from a dispatcher's office conventionally illustrated by the dotted rectangle DO. The signals at the west end of single track section O are governed by a control relay Z¹ and the signals at the east end of said single track section are controlled by control relay Z², these signal control circuits have been shown in part but need not be described in view of the disclosure in my prior application. These control relays Z¹ and Z² are polar-neutral relays in the particular arrangement shown, although three position relays may be used, and they are controlled by levers L¹ and L², respectively, located in the dispatcher's office DO.

Operation Fig. 1.—Let us assume that the dispatcher in the dispatcher's office DO wishes to permit traffic to move in an easterly direction, from left to right, and in order to do so moves the lever L¹ to the right hand dotted position. With the lever L¹ assuming the right hand dotted position the control

relay Z^1 located at the distant passing siding PS^1 is energized through the following circuit:—Beginning at the battery 40, wires 41 and 42, contact of the lever L' , wire 43, winding of the control relay Z^1 , wire 44, to common return wire RC connected to the mid point of battery 40. The direction of current flow established in this circuit causes the control relay Z^1 to be energized to the right-hand position, in which position it causes clearing of the signal 2, providing the home relay $2H$ is in its energized position. Also, with the control relay Z^1 energized the auxiliary stick relay ZS^1 is energized providing the home relay $2H$ is in its energized condition, and through the following circuit:—starting at the terminal B of a suitable current source, front contact 45 of the home relay $2H$, wire 46, front contact 47 of the control relay Z^1 , wire 48, winding of the auxiliary stick relay ZS^1 , to the common return wire C connected to the other terminal of said source.

The completion of this circuit causes the auxiliary stick relay ZS^1 to assume its energized condition. As soon as it has assumed such energized condition it will be stuck up through the following stick circuit:—beginning at the terminal B, front stick contact 50 of the relay ZS^1 , wires 51 and 46, front contact 47 of the control relay Z^1 , wire 48, winding or stick relay ZS^1 to the return wire C . With this stick relay ZS^1 in its energized condition the tumble-down circuit blocking west bound traffic is broken at the contact 15, and the home relay $3H$ and $7H$ are deenergized. The dispatcher will next operate his lever L^2 to the right hand position (assuming that east bound traffic is to enter the main track of passing siding PS^2), and with the lever L^2 in the right hand position for the following circuit for the control relay Z^2 is closed:—starting at the battery 40, wires 41 and 55, contact of the lever L^2 in the right hand dotted position, line wire 56, winding of the control relay Z^2 , common return wire RC to the middle point of battery 40. The completion of this circuit causes the control relay Z^2 to assume its right hand energized position and causes it to close its neutral contacts, thereby tending to cause the signal 7 to assume the clear position. This signal 7 cannot, however, be cleared because the home relay $3H$ is in its de-energized condition. Also, with the control relay Z^2 energized the pick up circuit for the auxiliary stick relay ZS^2 is closed at one point, but with the home relay $7H$ in its de-energized condition and its front contact 58 open, the auxiliary stick relay ZS^2 cannot be picked up. With the control relay Z^2 in its energized condition and home relay $7H$ de-energized no west bound direction of traffic can be set up in the single track section O, but if traffic conditions in advance of the signal 8 are favorable, this signal 8 will clear

and permit east bound traffic to move. It is thus noted that if the lever L^1 and L^2 are moved in the sequence L^1 , L^2 , the auxiliary stick relay ZS^1 will be energized while the auxiliary stick relay ZS^2 will remain de-energized.

Should now workmen along the track short circuit the track rails, as by getting a crow-bar across the rails, the condition of the stick relay ZS^1 could not be disturbed, and eventually the original direction of traffic would again be set up. In other words, in the system shown and described, a particular direction of traffic may be set up by the sequence in which control levers in the tower are moved, and if a certain direction of traffic has once been established this direction of traffic will again be set up even though the direction of traffic is blocked both ways, for a time, due to interference or tampering with the signal system, as by momentary breaking of circuit connection, opening of relay contacts or binding post connections, or momentary short circuiting of the track rails.

As just mentioned, if a particular direction of traffic has been set up by the showing in Fig. 1 of the drawings, and traffic is temporarily blocked for that direction, possibly because a track relay is de-energized for reasons other than a train moving in that same direction, the direction of travel originally established will be re-established as soon as such relay is re-energized. On the other hand, if the two levers common to a particular single track section are operated in sequence, but are operated one after another with a very short intervening lapse of time, traffic is blocked in both directions, because both of relays ZS^1 and ZS^2 will have assumed their energized condition.

The operator at the tower would, of course, not be informed of this fact (traffic blocked in both directions) by the arrangement shown in Fig. 1, and the movement of trains might be seriously delayed. For this reason, it is proposed in accordance with the present invention as shown in Fig. 2, to provide the train dispatcher with indicating means effective if traffic has been blocked in both directions in a single track section by reason of the energized condition of both relays ZS^1 and ZS^2 . In other words, Fig. 2 shows the west end of the single track section O of the system shown in Fig. 1 with the provision of indicating means for indicating when the stick relays ZS^1 and ZS^2 are both stuck up, the condition of energization of the relay ZS^2 being indicated by the condition of the relays $2H$ and $2S$. In this connection it should be remembered that the relay $2H$ is never de-energized if an east bound direction of traffic has been set up in the single track section O, except in response to a departing train between the signals 2 and 6, and when there is such an east bound train moving between the

signals 2 and 4 the stick relay 2S will be up. The relay 2S (see Fig. 1) is picked up through contacts 66 and 67 when an east-bound train passes the signal 2 or 2^d at clear or caution, and is stuck up through contacts 68 and 69 when the home relay 2H drops in response to such departing train. In other words, the relays 2H and 2S are never both de-energized unless the tumble-down circuit controlling relay 2H is open. For this reason if the relays 2H and 2S are both de-energized and the stick relay ZS¹ is also in its energized condition, is clear evidence that both directions of traffic are blocked for the single track section O. In other words, it is desirable to indicate to the dispatcher in the tower DO when the relays 2H and 2S are de-energized and the relay ZS¹ is energized.

It should be noted that the front contacts 60 of relay 2H front contact 61 of relay 2S, and the back contacts 62 of the relay ZS¹ are all connected in multiple with the back contact 63 of the relay OS, so that if relay ZS¹ is energized relay 2H is de-energized and relay 2S is left normal (de-energized) the contact 63 of the relay OS is unshunted and is therefore effective to control the circuit for the track repeater relay TR which relay repeats the detector track relay DT².

It is believed expedient to first briefly consider how occupancy of the detector track circuit containing track relay DT² is indicated, this feature already having been described generally in my prior application Ser. No. 221,037, filed Sept. 21, 1927, and also disclosed in the application of Dodgson Ser. No. 187,508, filed April 29, 1927. In the tower DO is located an indicating lamp IL, which is preferably associated with a track layout as described in my prior application so as to inform the operator which detector track circuit of the various track circuits under his jurisdiction is occupied. This indicating lamp IL is controlled in accordance with the position of the lever L¹ and the condition of energization of the indicating relay IR.

Let us assume that the operator has moved the lever L¹ (see Fig. 2) to the right hand position and has thereby caused the relay Z¹ to assume its right hand energized position through closure of the following circuit:—beginning at the battery 40, wire 41, lever L¹, wire 43, indicating relay IR, wire 43^a, front contact 43^b of the relay OS, wire 43^c, winding of the control relay Z¹, wires 44 and RC back to the battery 40. With the lever L¹ on its right hand position the circuit for the indicating lamp IL is completed at the contact L^a, but the indicating lamp IE is not illuminated because its circuit is broken at the back contact 64 of the indicating relay IR. The energization of the control relay Z¹ presumably clears either the signal 1 or the signal 2, depending upon the direction of traffic that has been set up in the single track section O. In

any event, let us assume that a west bound train enters upon the detector track circuit containing the track relay DT² in response to clearing of the signal 1, and that such treading of the train on this detector track circuit de-energizes the track relay DT². With the detector track relay DT² de-energized the energizing circuit for the repeater track relay TR is broken at the front contact 65 of track relay DT². Dropping of the repeater track relay TR opens its contact 57 thereby de-energizing the relay OS. With the relay OS de-energized, the energizing circuit for relay Z¹ heretofore traced is broken, but this control relay Z¹ is maintained energized through the following stick circuit:—beginning at the battery 70, wire 71, polar contact 72 of the control relay Z¹, wire 73, neutral contact 74 of this control relay Z¹ wire 75, back contact 43^b of the relay OS, wire 43^c, winding of the control relay Z¹, wires 44 and 76, back to battery 70. The control relay Z¹ thus remains in the same energized condition. Dropping of the contact 43^b of the relay OS however de-energizes the indicating relay IR, and such de-energization of relay IR causes the indicating lamp IL to be illuminated through completion of the following circuit:—starting with the terminal B, wire 77, back contact 64 of the indicating relay IR, wire 78, contact L^a, wires 79 and 80, indicating lamp IL, to common return wire C connected to the other side of the source of energy containing terminal B. The train dispatcher is thus informed of the occupancy of the detector track circuit in question.

Let us now assume that the lever L¹ has been returned to the neutral position and that the lever L² (see Fig. 1) is also in its neutral position. Under this condition the home relay 2H (see Figs. 1 and 2) assume its energized condition, this on the assumption that there are no trains in the single track section O.

Let us now assume that the operator, contrary to instructions, he having been instructed to allow a certain time to elapse between movement of adjacent levers, moves the levers L¹ and L² very quickly in succession, and that both of the relays ZS¹ and ZS² (see Fig. 1) will be picked up, because the auxiliary relays ZS¹ and ZS² both assume their energized position before the home relays 7H and 2H will have had sufficient time to assume their de-energized position. This rapid sequence of lever movement will thus cause the auxiliary stick relays ZS¹ and ZS² to be both stuck up, thereby causing the home relay 7H and 2H both to be held de-energized and thereby blocking traffic in both directions. With the relays 2H and 7H held de-energized in this way the associated stick-relays 2S and 7S (of which 7S is not shown) will of course remain de-energized. Referring now to Fig. 2 of the drawings, and bearing in mind that

the relays 2H and 2S are de-energized and the relay ZS¹ is energized, it is noted that the energizing circuit for the repeater track relay TR is broken. This causes the relay OS to assume its de-energized condition, thereby causing illumination of the indicating lamp IL for reasons heretofore given. This illumination of the indicating lamp IL, however, is only momentary, because de-energization of the relay OS completes an auxiliary circuit for the repeater track relay TR which circuit may be traced as follows:—beginning at the terminal B of a suitable source of current, wire 81, back contact 63 of the relay OS, wires 82 and 83, winding of the repeater track relay TR, wire 84, front contact 65 of the detector track relay DT², wire 85 to the terminal C connected to the other side of said source. With this circuit completed the repeater track relay is energized thereby re-energizing the relay OS and again completing the original energizing circuit for the relays Z¹ and IR, and thereby again extinguishing the indicating lamp IL. Obviously, this momentary illumination and extinguishing of the indicating lamp IL is repeated in see-saw fashion, and this indicating lamp is caused to flash or blink thus giving an indication to the dispatcher, distinctive from the indication of detector track circuit occupancy, and informing him that he has operated his levers in succession too quickly, and has caused traffic to be blocked for both directions of movement in the single track section O.

Although the invention has been shown applied to a system wherein detector track circuit occupancy is indicated by specific means and circuits, it is desired to be understood that any suitable means may be used for indicating track circuit occupancy or that no track circuit occupancy need be indicated if desired, for instance, if desired the contact 65 in the control circuit for the relay TR may be omitted. In the same way certain other contacts and devices may be omitted so long as the underlying principles of the invention are carried out.

Applicant has thus disclosed, not only a system in which the direction of traffic set up by sequence of lever movement cannot be accidentally reversed, but has also disclosed means for distinctively indicating to the dispatcher over the same line circuit used for controlling the direction of traffic in the single track section, that he has operated his levers too quickly in succession and that he has blocked traffic in both directions thus informing him that he must return his levers to the neutral position and must again operate them in sequence allowing sufficient time for setting up the direction of train travel desired. In this connection it is to be understood that if the levers for a particular single track section have been operated too quickly in sequence, the indicating lamps associated with

the two detector track circuits at opposite ends of this single track section are both flashed.

Having thus shown and described one complete embodiment of the invention and having shown rather specific circuit arrangements for accomplishing the results desired, it is desired to be understood that the particular embodiment of the invention illustrated has been selected to disclose the underlying principles thereof, and it is to be understood that various changes, modifications, and additions may be made to adapt the invention to the particular railway system and train dispatching system to which the invention is to be applied, all without departing from the spirit or scope of the invention or the idea of means underlying the same, except as demanded by the scope of the following claims.

What I claim is:—

1. In combination, a dispatcher's office, two control relays located distant to the dispatcher's office, two levers in said office for controlling the energization of said control relays, means responsive to the sequence in which said control relays are energized if energized in succession with an intervening period of time, and means for indicating in the dispatcher's office when he has moved his levers in succession too quickly.

2. In a train dispatching system, the combination with a single track section having starting signals located at opposite ends thereof, a dispatcher's office containing levers for controlling said starting signals, means for clearing a starting signal at one end of said single track section in accordance with the sequence in which said levers are operated if they are not operated too quickly in succession, and means in said dispatcher's office for indicating when he has operated his levers one after another in less than a predetermined period of time.

3. In a train dispatching system, the combination with a single track section having a starting signal at each end thereof, a train dispatcher's office, two levers in said office one for each of said starting signals, interlocking means for permitting only the starting signal controlled by the first lever operated to clear when said two levers are operated in sequence with an intervening lapse of time, and means for indicating to the dispatcher when he has operated his levers in succession too quickly.

4. In a train dispatching system, the combination with a single track section signaled by a signal system of the absolute-permissive-block type including two tumble-down circuits one governing each direction of traffic, a control relay at each end of said single track section governing the tumble-down circuit governable from that end and controlled by a dispatcher in a distant dispatcher's office, means for preventing one control relay from controlling its tumble-down circuit if

the other control relay in the meantime has de-energized its tumble-down circuit, and means in the dispatcher's office for indicating to the dispatcher if he has energized the control relays so quickly in succession that the first control relay to be energized did not yet effect complete de-energization of the tumble-down circuit it controls before the other control relay was energized.

5. In combination with a single track railway signalling system of the absolute-permissive-block type, of train dispatching means superimposed thereon including an auxiliary stick relay at each end of a single track section of said system, means for interlocking said two auxiliary relays through the medium of the tumble-down circuits of the absolute-permissive-block system of said single track section, and means for indicating 70 in a distant dispatcher's office when both of these auxiliary stick relays have been energized in response to substantially simultaneous de-energization of said two tumble-down circuits.
6. In combination with a single track railway system of the absolute-permissive-block type including the usual tumble-down circuits and home relays, a control relay at each end of a single track section for controlling a 75 home relay at the other end of the single track section through a tumble-down circuit, means for preventing the home relay at one end of said single track section being de-energized by the control relay at the other end 80 of said single track section if the home relay at the other end is in its de-energized condition, and an auxiliary relay at each end of said single track section each of which may be energized only if the control relay at that end 85 is energized and the home relay at that end is energized.
7. In combination with a single track railway system of the absolute-permissive-block type including the usual tumble-down circuits and home relays, a control relay at each end of a single track section for controlling the home relay at the other end of the single track section through a tumble-down circuit, means for preventing the home 90 relay at one end of said single track section being de-energized by the control relay at the other end of said single track section if the home relay at the other end is in its de-energized condition, an auxiliary relay at each end of said single track section which may be energized only if the control relay at that end 95 is energized and the home relay at that end is energized.
8. In combination with a single track railway system of the absolute-permissive-block type including the usual tumble-down circuits and home relays, a control relay at each 100

end of a single track section for controlling the home relay at the other end of the single track section through a tumble-down circuit, levers in a distant dispatcher's office for controlling said control relays, means for preventing the home relay at one end of said single track section being de-energized by the control relay at the other end of said single track section if the home relay at the other end is in its de-energized condition, an auxiliary relay at each end of said single track section which may be energized only if the control relay at that end is energized and the home relay at that end is energized, and indicating means for indicating at a distant dispatcher's office when both of said auxiliary relays are energized, said indicating means informing the dispatcher that he has operated his levers too quickly in succession.

9. In a single track railway signalling system of the absolute-permissive-block type in which each of the home relays for each direction of traffic of a single track section is normally energized by a circuit including a front contact of the next home relay ahead governing the same direction of traffic, means at one end of a single track section for de-energizing the home relays governing traffic in said single track section moving toward that end, and means for manifesting whether the home relays for the opposite direction of travel were de-energized when the home relays in question were being de-energized.

10. In a single track railway signaling system of the absolute-permissive-block type including tumble-down circuits in which each of the home relays for each direction of traffic of a single track section are normally energized by a circuit including a front contact of the next home relay ahead governing the same direction of traffic, means at one end of a single track section for de-energizing the tumble-down circuit governing traffic in said single track section moving toward that end, and means for manifesting whether the tumble-down circuit for the opposite direction of traffic was de-energized when the tumble-down circuit in question was being de-energized.

11. In a single track railway signaling system of the absolute-permissive-block type including tumble-down circuits in which each of the home relays for each direction of traffic of a single track section is normally energized by a circuit including a front contact of the next home relay ahead governing the same direction of traffic, means at one end of a single track section for de-energizing the tumble-down circuit governing traffic in said single track section moving toward that end, 115 means for manifesting whether the tumble-down circuit for the opposite direction of traffic was de-energized when the tumble-down circuit in question was being de-energized, and means for indicating when both of 120

the tumble-down circuits are de-energized substantially simultaneously.

12. In combination with a single track railway signalling system of the absolute-permissive-block type, of train dispatching means superimposed thereon including an auxiliary stick relay at each end of a single track section of said system, means for interlocking said two auxiliary relays through the medium of the tumble-down circuits of the absolute-permissive-block system of said single track section, and means for indicating in a distant dispatcher's office when both of these auxiliary stick relays have been energized in response to simultaneous initiation of de-energization of said two tumble-down circuits in overlapped relation.

13. In combination, a dispatcher's office, two control relays located distant to the dispatcher's office, two levers in said office for controlling the energization of said control relays, means responsive to the sequence in which said control relays are energized if energized in succession with at least a predetermined intervening period of time, and means for indicating in the dispatcher's office when he has moved his levers in succession with a less intervening period of time than said predetermined period.

30 In testimony whereof I affix my signature.
SEDGWICK N. WIGHT.
